Primary Examiner — Paul Greene(74) *Attorney, Agent, or Firm* — McDonald Hopkins LLC(57) **CLAIM**

The ornamental design for a speaker with lighting, as shown and described.

DESCRIPTION

FIG. 1 is a front view of a speaker with lighting;

FIG. 2 is a back view thereof;

FIG. 3 is a plan view thereof;

FIG. 4 is a bottom view thereof;

FIG. 5 is a right view thereof;

FIG. 6 is a left view thereof; and,

FIG. 7 is an enlarged perspective view of the upper end of a speaker with lighting.

The broken lines shown in the figures are for illustrative purposes only and form no part of the claimed design.
